FLUORESCENT LAMP STARTER

Charles H. Hodgkins, Fairfield, and Oscar Hamersstrom, Bridgeport, Conn., assignors to The Bryant Electric Company, Bridgeport, Conn., a corporation of Connecticut

Application March 12, 1943, Serial No. 478,894

6 Claims. (Cl. 200—122)

The present invention relates to starting relays for fluorescent lamps and particularly to a thermal relay which automatically operates to start such lamps, and if for any reason the lamp fails to start after a predetermined period of time, the relay operates to disconnect the failed lamp from the source of supply and is automatically reset upon replacement of the failed lamp.

The primary object of the present invention is to provide a relay of this character which is simple and economical to manufacture.

Another object of the invention is the provision of an economical thermal relay for the starting of fluorescent lamps wherein separation of the contacts occurs with a positive and rapid break, thus eliminating arcing between the contacts.

Still further objects of the present invention will become obvious to those skilled in the art by reference to the accompanying drawing wherein:

Fig. 1 is a sectional view of the starting relay unit of the present invention and showing a front elevational view of the relay itself.

Fig. 2 is a fragmentary sectional view of the relay of Fig. 1 taken at 90° to the latter and showing the normal open position of the relay prior to its operating.

Fig. 3 is a sectional view taken on the line III—III of Fig. 1.

Fig. 4 is a sectional view taken on the line IV—IV of Fig. 1 and showing the closed circuit position of the relay.

Fig. 5 is a sectional view identical to Fig. 4 but showing the position of the relay in the "lock-out" position thereof which it assumes when a fluorescent lamp becomes defective.

Fig. 6 is a schematic diagram of the circuit for starting a fluorescent lamp and utilizing the thermal relay of the present invention.

Referring now to the drawing in detail, the starting relay of the present invention is shown generally at 5 in the several figures and is housed within a metallic or plastic casing 6 together with a radio-frequency-suppressing condenser 7, both of which are connected in electrical parallel to a pair of socket terminals 8 and 9 adapted to engage a socket and which are secured to an insulating closure member 10.

The relay itself comprises a base 12 of suitable insulating material such as fiber, a phenolic condensation product, hard rubber or the like, and as shown in Fig. 1 the base is provided with a pair of eyelets 13 and 14 which are connected to the socket terminals 8 and 9 by conductors 15 and 16, respectively. A high ohmic electrical resist-

ance heater 17 is electrically connected to the eyelets 13 and 14 by rod-like conductors 18 and 19 which also serve as a support for the heater so as to dispose the latter in spaced relation to the base 12. A bracket 20 (Fig. 2) extends outwardly from the base member 12 with one end thereof electrically connected to the eyelet 14, which bracket forms a support for one end of a U-shaped bimetallic element 22 which thus partially surrounds the high ohmic resistance heater 17.

A second bimetallic element 23 is secured to the free end of the bimetallic element 22 and is disposed in substantially parallel spaced relation above the latter throughout substantially the entire longitudinal axis thereof. As will be noted in the several figures, the bimetallic element 23 is of greater length than the bimetallic element 22 and a contact terminal 24 is affixed to the extending free end of the over-lapping bimetallic element 23. This contact is normally disposed in spaced relation to a stationary contact 25 spaced from the base and a low resistance heater element 26 is disposed in juxtaposition to the stationary contact 25 being electrically connected to the latter and to the eyelet 13. In addition, a bracket 27 is secured at one end to the base 12 and extends therefrom in an angular direction so as to form a stop 28 disposed in the path of movement of the joined ends of the bimetallic elements 22 and 23 as hereinafter more fully explained.

By reference now more particularly to Fig. 6, a fluorescent lamp 30 is therein shown provided with a pair of filamentary electrodes 32 and 33. One end of the filamentary electrode 32 is connected through an inductance 34 to one side of the source of supply L—1 of the customary domestic potential of 115 volts, and, similarly, one end of the filamentary electrode 33 is connected through a hand switch 35 to the opposite side of the supply source L—2. The remaining ends of the filamentary lamp electrodes 32 and 33 are connected together through the thermal relay device 5.

It will be noted that the high ohmic resistance heater element 17 being connected across the socket terminals 8 and 9 will accordingly receive full line voltage upon closure of the hand switch 35. The heat thus generated by the heater is transmitted by radiation to the adjacent bimetallic element 22. Inasmuch as one end of this latter bimetallic element is anchored to the bracket 20, it remains fixed, with the result that the free end thereof deflects away from the heater element and base 12. Since the bimetallic ele-

ment 23 is connected to the free end of the bimetallic element 22, it is carried with or by the free end of the bimetallic element 22, with the result that the contact 24 is carried by the extending free end of the bimetallic element 23 also moves away from the base into contact with the stationary contact 25 in the manner shown in Fig. 4.

The engagement of the movable contact 24 with the stationary contact 25 accordingly short-circuits the high ohmic resistance heater 17 and thus completes a heating circuit for the filamentary lamp electrodes 32 and 33 through the two bimetallic elements 22 and 23, the closed contacts 24 and 25 and through the low resistance heater 26. The short-circuiting of the high resistance heater element 17 accordingly stops the generation of heat, with the result that the shorter bimetallic element 22 begins to cool and return to its normal position as shown in Fig. 2.

However, the time during which the contacts 24 and 25 remain in engagement with each other is sufficient to enable the lamp electrodes 32 and 33 to be heated to optimum electron-emitting temperature. At the same time that the bimetallic element 22 is cooling, the extending free end of the longer bimetallic element 23 is being heated by conduction and radiation from the low resistance heater 26, with the result that such extending end deflects away from the stationary contact to its normal position simultaneously with cooling of the bimetallic element 22 causing the contacts 24 and 25 to separate positively and rapidly. Separation of these contacts 24 and 25 accordingly induces a high voltage surge from the inductance 34, thus initiating a discharge between the preheated filamentary lamp electrodes 32 and 33.

During operation of the lamp, lamp-operating voltage is impressed across the high ohmic resistance heater 17 which is of insufficient value to generate appreciable heat so that this heater has no effect upon the thermal relay during operation of the lamp, with the result that it will remain in the position as shown in Fig. 2. In the event the lamp 30 fails to start upon initial operation of the relay 5, the latter repeats its cycle of operation until the lamp starts. If, however, the lamp 30 is defective due to deactivation of its filamentary electrodes 32 and 33 and as a consequence the lamp fails to start after a predetermined period of time, the relay will "lock-out" the lamp 30. For example, upon initial separation of the contacts 24 and 25 full line voltage is again immediately impressed across the high ohmic resistance heater 17, resulting in cyclic operation of the relay for a predetermined period of time.

Each time that full line voltage is impressed across the high ohmic resistance heater 17, the heat transmitted to the bimetallic element 22 becomes accumulative, with the result that it continues to deflect until the free end thereof which carries the superimposed bimetallic element 23 engages the stop 28. Thus further deflection of the bimetallic element 22 is limited, resulting in the heat being conducted to the superimposed bimetallic element 23, causing its extending end to deflect away from the heater toward the base. Thus continued application of full line voltage to the high ohmic resistance heater 17 maintains the contacts 24 and 25 in a separated position, as shown in Fig. 5, until the defective lamp is replaced. Upon replacement of the defective lamp, the relay automati-

cally returns to its normal position as shown in Fig. 2 in condition for its cyclic operation for the starting of a lamp, as previously described.

It thus becomes obvious to those skilled in the art that a thermal relay for the starting of a gaseous electric discharge lamp is herein provided which is simple and economical to manufacture. Moreover, due to the provision of a low resistance heater element in juxtaposition to the stationary contact which applies heat during engagement of the contacts, they separate with positiveness and rapidity for the purpose of starting the lamp and without the formation of an arc which would otherwise detrimentally affect the contacts.

In addition, the relay operates upon the lamp becoming defective to "lock-out" the same, thus eliminating repetitious operation of the relay in a futile attempt to start the defective lamp with the relay remaining in its "locked-out" position until the defective lamp is replaced.

Although one embodiment of the present invention has been herein shown and described, it is to be understood that other modifications of the same may be made without departing from the spirit and scope of the appended claims.

We claim:

1. A thermal relay for gaseous electric discharge lamps comprising an electric resistance heater, a bimetallic element secured at one end and partially surrounding said heater with its free end deflectable away from said heater under heat from the latter, a second bimetallic element attached to the free end of said first mentioned bimetallic element and normally disposed in substantially parallel spaced relation above the latter throughout the entire longitudinal axis thereof, a stationary contact, a contact carried by the free end of said second mentioned bimetallic element and movable into engagement with said stationary contact by deflection of said first mentioned bimetallic element under heat from said heater to short-circuit the latter, and a low resistance heater adjacent said stationary contact and operable upon engagement of said contacts with attendant short-circuiting of said first mentioned heater and cooling of said first mentioned bimetallic element to heat said second mentioned bimetallic element and cause deflection of the latter with a positive and rapid separation of said movable contact from said stationary contact.

2. A thermal relay for gaseous electric discharge lamps comprising an electric resistance heater, a bimetallic element secured at one end and partially surrounding said heater with its free end deflectable away from said heater under heat from the latter, a second bimetallic element of greater length than said first mentioned bimetallic element attached to the free end of the latter and normally disposed in substantially parallel spaced relation above said first mentioned bimetallic element throughout the entire longitudinal axis thereof, a stationary contact, a contact carried by the extending free end of said second mentioned bimetallic element and movable into engagement with said stationary contact solely by deflection of said first mentioned bimetallic element under heat from said heater to short-circuit the latter, and a low resistance heater adjacent said stationary contact and operable upon engagement of said contacts with attendant short-circuiting of said first mentioned heater and cooling of said first mentioned bimetallic element to heat the extending free end

of said second mentioned bimetallic element and cause deflection of the latter in an opposite direction with positive and rapid separation of said movable contact from said stationary contact.

3. A thermal relay for gaseous electric discharge lamps comprising a base, an electric resistance heater supported by said base, a substantially U-shaped bimetallic element supported at one end from said base and partially surrounding said heater and operable to deflect away from said base under heat from said heater, a second bimetallic element of greater length than said first mentioned bimetallic element to increase the distance of deflection thereof attached to the free end of the latter and normally disposed in substantially parallel spaced relation above said first-mentioned bimetallic element throughout the entire longitudinal axis thereof, a stationary contact supported by said base, a contact carried by the free end of said second mentioned bimetallic element normally spaced from said stationary contact and movable into engagement therewith solely by deflection of said first mentioned bimetallic element away from said base under heat from said heater to short-circuit the latter, and a low resistance heater in juxtaposition to said stationary contact and operable upon engagement of said contacts with attendant short-circuit of said first mentioned heater and cooling of said first mentioned bimetallic element to heat the extending end of said second mentioned bimetallic element and cause deflection of the latter toward said base with a positive and rapid separation of said movable contact from said stationary contact.

4. A thermal relay for gaseous electric discharge lamps comprising an electric heater, a bimetallic element secured at one end and partially surrounding said heater with its free end deflectable away from said heater under heat from the latter, a second bimetallic element attached to the free end of said first mentioned bimetallic element and normally disposed in substantially parallel spaced relation above the latter throughout the entire longitudinal axis thereof, a stationary contact, a contact carried by the free end of said second mentioned bimetallic element and normally movable into engagement with said stationary contact solely by deflection of said first mentioned bimetallic element under normal heat from said heater to short-circuit the latter, and means disposed in the path of deflection of said first mentioned bimetallic element to limit movement thereof upon undue heating by said heater following failure of the discharge lamp to start after cyclic operation of said relay for a predetermined period of time and for causing the resultant heat to deflect said second mentioned bimetallic element and maintain said contacts in a separated position until replacement of the discharge lamp.

5. A thermal relay for gaseous electric discharge lamps comprising an electric heater, a bimetallic element secured at one end and partially surrounding said heater with its free end deflectable away from said heater under heat from the latter, a second bimetallic element attached to the free end of said first mentioned bimetallic element and normally disposed in substantially parallel spaced relation above the latter throughout the entire longitudinal axis thereof, a stationary contact, a contact carried by the free end of said second mentioned bimetallic element and normally movable into engage-

ment with said stationary contact solely by deflection of said first mentioned bimetallic element under normal heat from said heater to short-circuit the latter, and a stop disposed in the path of deflection of said first mentioned bimetallic element to limit deflection thereof upon undue heating by said heater following failure of the discharge lamp to start after cyclic operation of said relay for a predetermined period of time and for causing the resultant heat to deflect said second mentioned bimetallic element and maintain said contacts in a separated position until replacement of the discharge lamp.

6. A thermal relay for gaseous electric discharge lamps comprising an electric heater, a bimetallic element secured at one end and partially surrounding said heater with its free end deflectable away from the anchored end when heated by said heater, a second bimetallic element of greater length than said first mentioned bimetallic element attached to the free end of the latter and normally disposed in substantially parallel spaced relation above said first mentioned bimetallic element throughout the entire longitudinal axis thereof, a stationary contact, a contact carried by the free end of said second mentioned bimetallic element and normally movable into engagement with said stationary contact solely by deflection of said first mentioned bimetallic element under normal heat from said heater to short-circuit the latter, and a stop positioned to be engaged by the joined ends of said bimetallic elements to limit deflection thereof upon undue heating of said heater following failure of the discharge lamp to start after cyclic operation of said relay for a predetermined period of time and for causing the resultant heat to deflect the extending end of said second mentioned bimetallic element in a direction opposite to its movement under the influence of said first mentioned bimetallic element to maintain said contacts in a separated position until replacement of the discharge lamp.

7. A thermal relay for gaseous electric discharge lamps comprising an electric resistance heater, a bimetallic element secured at one end and partially surrounding said heater with its free end deflectable away from said heater under heat from the latter, a second bimetallic element attached to the free end of said first mentioned bimetallic element and normally disposed in substantially parallel spaced relation above the latter throughout the entire longitudinal axis thereof, a stationary contact, a contact carried by the free end of said second mentioned bimetallic element and normally movable into engagement with said stationary contact solely by deflection of said first mentioned bimetallic element under normal heat from said heater to short-circuit the latter, a low resistance heater adjacent said stationary contact and operable upon engagement of said contacts with attendant short-circuiting of said first mentioned heater and cooling of said first mentioned bimetallic element to heat said second mentioned bimetallic element and cause deflection of the latter with a positive and rapid separation of said movable contact from said stationary contact, and means disposed in the path of deflection of said first mentioned bimetallic element to limit movement thereof upon undue heating by said heater following failure of the discharge lamp to start after cyclic operation of said relay for a predetermined period of time and for causing the resultant heat to deflect said second mentioned

bimetallic element and maintain said contacts in a separated position until replacement of the discharge lamp.

8. A thermal relay for gaseous electric discharge lamps comprising an electric resistance heater, a bimetallic element secured at one end and partially surrounding said heater with its free end deflectable away from said heater when heated by the latter, a second bimetallic element of greater length than said first mentioned bimetallic element attached to the free end of the latter and normally disposed in substantially parallel spaced relation above said first mentioned bimetallic element throughout the entire longitudinal axis thereof, a stationary contact, a contact carried by the free end of said second mentioned bimetallic element and normally movable into engagement with said stationary contact solely by deflection of said first mentioned bimetallic element under normal heat from said heater to short-circuit the latter, a low resistance heater in juxtaposition to said stationary

contact and operable upon engagement of said contacts with attendant short-circuiting of said first mentioned heater and cooling of said first mentioned bimetallic element to heat the ext-
5 tending end of said second mentioned bimetallic element and cause deflection of the latter in an opposite direction with positive and rapid separation of said movable contact from said stationary contact, and a stop engageable by the 10 joined ends of said bimetallic elements to limit deflection thereof upon undue heating of said heater following failure of the discharge lamp to start after cyclic operation of said relay for a predetermined period of time and for causing the resultant heat to deflect the extending end of said second mentioned bimetallic element in a direction opposite to its movement under the influence of said first mentioned bimetallic element 15 to maintain said contacts in a separated position until replacement of the discharge lamp.

CHARLES H. HODGKINS,
OSCAR HAMMERSTROM.
